[57] CLAIM

The ornamental design for a vacuum cleaner upper portion, as shown and described.

DESCRIPTION

FIG. 1 is a top front and left side perspective view of a vacuum cleaner upper portion showing our new design; FIG. 2 is a top plan view thereof;

FIG. 3 is a bottom plan view thereof;

FIG. 4 is a left side elevational view thereof;

FIG. 5 is a front elevational view thereof;

FIG. 6 is a right side elevational view thereof; and,

FIG. 7 is a rear elevational view thereof.

The portion of the vacuum cleaner shown in broken lines in FIG. 1 is shown for illustrative purposes only and forms no part of the claimed design.
